ARTHUR R. GABRIEL, OF NEW YORK, N. Y., ASSIGNOR TO SAMUEL GABRIEL SONS AND COMPANY, OF NEW YORK, N. Y., A CORPORATION OF NEW YORK.

TOY DOLL.

1,319,384.

Specification of Letters Patent.

Patented Oct. 21, 1919.

Application filed July 12, 1919. Serial No. 310,363.

To all whom it may concern:

Be it known that I, ARTHUR R. GABRIEL, a citizen of the United States, and a resident of New York, in the county and State of 5 New York, having invented certain new and useful Improvements in Toy Dolls, do hereby declare that the following is a full, clear, and exact description of the same.

This invention relates to toy dolls and 10 more particularly to toys of that general class commonly known as "cut-out" dolls, which are constructed of cardboard or other suitable material having the requisite durability.

15 It is the primary object and purpose of the present invention to provide a toy doll having simple and novel means for realistically simulating the opening and closing movements of the eyelids, so that 20 the doll may appear to be wide awake or fast asleep.

More particularly, the present improvements comprehend the provision of a representation of the eyes suitably secured to the 25 back of the head of the figure and visible through the eye openings and a slideable member movable between the part upon which the eyes are represented and the head and suitably guided in a continuous straight 30 line, said member having the eyelids represented thereon, and being disposed at its upper end through a slit in the head and formed to represent a bow of ribbon having the appearance, in either position of said 35 member, of being tied to the hair.

It is a further general object of my invention to provide a toy doll as above characterized, which is very simple and may be manufactured and sold at a comparatively 40 small cost and will afford considerable amusement to children.

With the above and other objects in view, the invention consists in the improved construction, combination and relative arrangement of the several parts, as will be hereinafter more fully described, illustrated in 45 the accompanying drawings, and subsequently incorporated in the subjoined claims.

In the drawing wherein I have illustrated 50 one practical embodiment of my invention, and in which similar reference characters designate corresponding parts throughout the several views,

Figure 1 is an elevation illustrating the 55 toy doll, the eyelids being in open position;

Fig. 2 is a similar view of the head portion of the doll, the eyelids being closed.

Fig. 3 is a rear elevation;

Fig. 4 is a section taken on the line 4—4, 60 Fig. 3;

Fig. 5 is a front elevation of a slightly modified form of the device and

Fig. 6 is a rear elevation of the modified construction.

Referring in detail to the drawing, more 65 particularly to Figs. 1 to 4 thereof, 5 designates the body of the doll and 6 the head portion thereof, the latter having a representation of hair, as shown at 7. The figure is cut out in outline from a sheet of card- 70 board or other suitable material of the requisite thickness and durability, and as will be readily understood may be of any desired size.

The head 6 of the figure is provided with 75 eye openings shown at 8, and to the rear side of the head, a sheet of paper or cardboard 9 is secured at its marginal edges preferably by means of a suitable adhesive. Upon this sheet of material the eyes 10 are 80 printed, painted or otherwise properly represented and are visible through the openings 8.

A slide member 11 is vertically shiftable between the rear face of the head 6 and 85 the cardboard sheet 9, and the relatively wide upper end portion 12 of this slide member extends through a horizontal slot 13 cut above the forehead of the head 6 and in the portion of the head represented by the 90 hair 7. The member 11 is provided with a relatively narrow portion 14 extending downwardly from the wider portion 12 thereof, and movable in the guides 15 which are secured to the rear side of the head 6. 95 These guides may be formed either of cardboard or sheet metal. A tongue 16 is struck out from the lower end of the portion 14 of the slide but remains integrally connected therewith. This tongue coating with the 100 lower edge of the cardboard piece 9 limits the upward movement of the slide member 11 in the guides.

Upon the lower edge of the wider portion 12 of the slide member and at each side 105 of the relatively narrow downwardly extending portion 14, the eyelids 17 are represented. As seen in Fig. 1 of the drawing, the slide member is at the limit of its upward movement so that the eyelids are dis- 110

posed above the eye openings, the eyes 10 being visible therethrough. In this position, therefore, the doll appears to be awake.

5 The upper end of the slide member which extends through the slot 13 terminates in a widened portion cut to represent a ribbon bow 18. The slot 13 it will be observed is slightly curved, and the lower loops 19 of 10 the bow 18 at the opposite ends thereof project downwardly through the slot and are not entirely withdrawn therefrom even when the slide member is moved upwardly to the limit of its movement. The representation of the bow will therefore always 15 present a very realistic appearance and simulate a hair ornament, so that when the figure is placed at a slight distance from the observer the line of the slot 13 will not be easily 20 discernible and the presence of the slide member 11 carrying the movable eyelids will hardly be suspected.

The end edges of the lower loops of the bow 18 are curved as at 20, the lower parts 25 of the loops extending below the slot 13 until the end edges 20 come into contact with the ends of the slot, thereby limiting the downward movement of the slide member at which time the lids 18 are disposed over the 30 eyes in their closed positions as seen in Fig. 2. Thus the eyelids will be accurately placed with respect to the openings 8 and afford a very realistic representation of a sleeping doll. In this position of the slide 35 member it is to be observed that the extremities of the upper loop portions of the bow 18, project laterally beyond the edge of the head as seen at 21 and thereby afford means with which the thumb and forefinger of the 40 hand may be readily engaged to shift the slide member in the desired direction.

In Figs. 5 and 6 of the drawing, I have shown a slightly modified form of the device wherein the narrow downwardly extending portion 14' of the slide member is provided with a slot 22 to receive the end of a split pin 23 the separate portions of the pin being bent laterally in opposite directions, and serving to guide the slide member 50 in its movement. The head 24 of this pin is disposed upon the front of the figure at the neck. A necklace indicated at 25 is preferably printed upon the figure in this form of the device, and is represented as composed of 55 beads of substantially the same diameter as the diameter of the pin head 24. Thus the pin head will not be easily distinguishable from the beads and will not detract from the realistic appearance of the figure.

60 From the foregoing description considered in connection with the accompanying drawing, the construction and manner of operation of my improved toy doll will be readily understood. The parts of the device may be 65 readily stamped or cut out and secured upon

the figure in their assembled positions with a few minor operation, so that the manufacturing cost of the improved toy doll will be relatively small. While, as illustrated in the drawings, I prefer to form the upper 70 end of the slide member in representation of a ribbon bow, it is manifest that if desired the upper end of the slide may be cut to represent a hair ornament of any other desired character. 75

While I have herein shown and described the preferred form, construction and relative arrangement of the parts, my invention may nevertheless be exemplified in numerous other alternative constructions, and I accordingly reserve the privilege of adopting all such legitimate changes as may be fairly embodied within the spirit and scope of the invention as claimed. 80

I claim:

1. A toy figure having a head part provided with eye openings, a part secured to the rear side of said head part and having eyes represented thereon visible through said openings, a slide member movable between 90 the latter part and the head and having eyelids represented thereon which when said member is moved in one direction extend over the eyes and simulate the closing of the eyes, said head part having a slot formed 95 therein through which the upper end of the slide member extends, and said slide member being formed at its upper end to represent an ornament disposed upon the front side of the head. 100

2. A toy figure having a head part provided with eye openings, a part secured to the rear side of said head part and having eyes represented thereon visible through said openings, a slide member movable between 105 the latter part and the head and having eyelids represented thereon which when said member is moved in one direction extend over the eyes and simulate the closing of the eyes, said head part having a slot formed 110 therein through which the upper end of the slide member extends, and said slide member being formed at its upper end to represent an ornament disposed upon the front side 115 of the head, the ends of said ornament projecting laterally beyond the marginal edges of the head part and providing portions easily engageable to actuate said slide member. 120

3. A toy figure having a head part provided with eye openings, a part secured to the rear side of said head part and having eyes represented thereon visible through said openings, a slide member movable between 125 the latter part and the head and having eyelids represented thereon which when said member is moved in one direction extend over the eyes and simulate the closing of the eyes, said head part having a slot formed 130 therein through which the upper end of the

slide member extends and the said slide member being formed at its upper end to represent an ornament disposed upon the front side of the head, parts of which at all times extend through and below said slot, the end edges of the ornament being curved for binding engagement with the head part at the ends of the slot to limit the downward movement of the slide member and thereby accurately locate the eyelids in their closed positions relative to the eye openings.

4. A toy figure having a head part provided with eye openings, a part secured to the rear side of said head part and having eyes represented thereon visible through said openings, a slide member movable between the latter part and the head and having eyelids represented thereon which when said member is moved in one direction extend over the eyes and simulate the closing of the eyes, said head part having a slot formed therein through which the upper end of the slide member extends and said slide member being formed at its upper end to represent an ornament disposed upon the front of the head, parts of which at all times extend through and below said slot, the end edges of the ornament being curved for binding engagement with the head part at the ends of the slot to limit the downward movement of the slide member and thereby accurately locate the eyelids in their closed positions relative to the eye openings, and other parts of the ornament projecting laterally beyond the marginal edge of the head part and affording finger engaging portions

whereby the slide member may be conveniently actuated.

5. A toy figure having a head part provided with eye representations and means for simulating the opening and closing movements of the eyes, said means consisting of a slide member having eyelids represented thereon, guides for said member secured to the rear side of the head part, said head part having a horizontal slot therein and the upper end of the slide member projecting through said slot and having a terminal portion disposed upon the front side of the head formed to represent a hair ornament.

6. A toy figure having a head part provided with eye representations and means for simulating the opening and closing movements of the eyes, said means consisting of a slide member having eyelids represented thereon, guides for said member secured to the rear side of the head part, said head part having a horizontal slot therein and the upper end of the slide member projecting through said slot and having a terminal portion disposed upon the front side of the head formed to represent a hair ornament, parts of said ornament projecting through the opposite ends of the slot and adapted for binding engagement with the head part to limit the movement of the slide member whereby the eyelids are accurately located in their closed positions.

In testimony that I claim the foregoing as my invention, I have signed my name hereunder.

ARTHUR R. GABRIEL.
